UNITED STATES PATENT OFFICE.

ANDREW J. CHASE, OF BOSTON, MASSACHUSETTS.

REFRIGERATING APPARATUS.

SPECIFICATION forming part of Letters Patent No. 374,114, dated November 29, 1887.

Application filed October 23, 1886. Renewed November 1, 1887. Serial No. 254,013. (No model.)

To all whom it may concern:

Be it known that I, ANDREW J. CHASE, a citizen of the United States, residing at Boston, in the county of Suffolk and State of Massachusetts, have invented new and useful Improvements in Refrigerating Apparatus, of which the following is a specification.

In refrigerator cars, vessels, and other structures where tanks are employed to contain the refrigerant mixture of ice and salt the resultant of the mixture is a pickle or brine composed of a freezing mixture of water and salt.

The objects of my invention are to provide novel means for maintaining the ice and pickle separated from each other in the ice-tank, and to provide a novel construction of ice-tank for utilizing the refrigerating properties of the pickle.

The objects of my invention I accomplish in the manner and by the means hereinafter described and claimed, reference being made to the accompanying drawings, in which—

Figure 1 is a sectional elevation of a refrigerator-car embodying my invention; Fig. 2, a detail vertical sectional view through one of the ice-tanks and the roof of the car, and Fig. 3 a horizontal sectional view taken on line xx of Fig. 1.

In order to enable those skilled in the art to make and use my invention, I will now describe the same in detail, reference being made to the drawings, where I have shown my invention embodied in the construction of a refrigerating railway-car; but, obviously, the invention can be embodied in steamships, vessels, and other structures, whether traveling or stationary.

The numeral 1 indicates the wooden walls of the structure, having around one end a series of standards or stanchions, 2, to which is secured the rectangular or similar shaped metallic casing 3 across the car, which casing is thereby separated from the end and side walls of the car by an intervening air-circulating space, 4, in such manner that the casing is detached from the wooden walls. By this arrangement, if the external air, with its heat and moisture, should pass through the wooden walls, the contained moisture in such air will be taken up by the cold metallic surface 50 of the casing at a distance from the wooden walls, leaving the air dry, and the condensed moisture will drip from the casing into the

drip-pan 5, keeping the wooden walls dry and preventing them from becoming saturated to such an extent as to impair their non-conducting properties where employed in air-tight freezing compartments. The casing is open at both top and bottom, as at 6, so that the air circulates between it and the wooden walls; and within the said casing are placed a series 55 of metallic ice-tanks, 7, having imperforate walls, of oval, cylindrical, or similar shape, in cross-section, bearing against the opposite sides of the casing, while the end tanks bear against the ends as well as the sides thereof. In each 60 tank is located a horizontal division-wall, 8, of wood or other material, having perforations or passages and dividing the tank into an upper ice-receiving chamber, 9, and a lower pickle-receiving chamber, 10, the lower end of which 65 is closed by a wooden or other bottom, 11, having a single orifice, 12, which can be opened and closed by a plug or valve, 13, connected with a rod, 14, extending up through the tank to or near the roof or top wall of the car or 70 other structure.

A dividing vertical partition, 15, extends across the car from side to side between the casing and the preserving-compartment 18, and is held and supported at a slight distance away 80 from the inner side wall of the lining or casing by interposed wooden strips to provide an air-passage between the casing and the partition, the latter terminating at a short distance from the floor and roof of the car, as at 16 and 17, 85 to permit the automatic circulation of air from the preserving-compartment 18, around the partition, the tanks, and the detached metallic casing. The upper ends of the tanks open into an ice-supply trunk or hopper, 19, extending 90 across the roof of the car and common to all the tanks, so that the latter will be maintained full of ice. The trunk or hopper is filled with ice by removing its cover 20, and acts as a feeder to the tanks, and where the invention 95 is applied to a railway-car the vibrations thereof serve to automatically feed the ice into the tanks.

The walls comprising the casing, as well as the walls of the tanks, overhang the drip-pan 100 5, which is placed in or on the floor of the car or other structure in such manner that the drippings resulting from condensation are received by the pan, and escape therefrom by a

suitable outlet, 21, which may, if desired, discharge into a suitable vessel or receiver.

A metallic or other suitable apron, 22, is suspended in each tank and forms a close joint 5 with the horizontal division-wall 8, to which it may be secured, such apron conforming in cross-section to the form of the tank, or substantially so, but of a less diameter than the tank, so as to provide a surrounding unobstructed vertical space, 23, between the apron and the walls of the tank. The apron terminates at its lower edge a short distance above the bottom wall of the pickle-chamber to provide a space, 24, and the walls of each tank at 15 some suitable point beneath the division-wall 8 are provided with lateral outlet-orifices 25. The space 23 holds a stratum or column of pickle between the apron and the wall of the tank for constantly absorbing heat, thereby 20 raising the temperature of such stratum or column. The descending pickle, resulting from the ice and salt mixture, forces the stratum or column to gradually assume a higher altitude, until finally it escapes through the outlet- 25 orifices 25, but not until such stratum has effected its purpose of absorbing heat, and thus enlarging the refrigerating capacity of the apparatus. As will be obvious, the descending cold pickle and ascending stratum of pickle 30 cause a continuous but slow circulation, the stratum constantly absorbing heat and the descending pickle pressing on the stratum and forcing it upward.

The pickle can be discharged from the 35 pickle-chamber by operating the plug or valve 13 through its rod 14, to open the orifice 12. The pickle or brine, which has a commercial value, can be drawn off and used from time to time for pickling purposes.

40 The walls comprising the casing increase the cooling and condensing surface, induce a rapid circulation of air, and, touching the external surfaces of the imperforate walls of all the tanks, become a frost-bearing plant by 45 conduction. The walls of the casing overhang the drip-pan and present its inner and outer surfaces to the circulating air, whereby the cooling capacity of a given size of refrigerating apparatus is largely increased.

50 The division-walls in the tanks maintain the ice in the upper part from contact with the pickle in the pickle-chamber, and also prevent the ice from forcing out the pickle by displacement, as occurs where the ice rests or 55 floats directly in the brine.

The tanks are suspended and held by their

upper ends being secured to or connected with the roof or top of the car or other structure, and the metallic casing, as well as the partition, are of less height than the tanks, so that 60 the casing is open at its upper and lower ends; but, obviously, such open ends may be otherwise produced, so long as the construction is such that the circulating air can pass, as indicated by the arrows, along both surfaces of 65 the casing and the external surfaces of the tanks. The tanks have a circular or oval form in cross-section, so that they only have contact with the casing at certain points and permit the free circulation of the air about the 70 imperforate walls of the tank, so that the circulating air is preserved in a dry condition, as it never comes in contact with the ice in the tanks, as is the case in the construction of refrigerator for which Letters Patent No. 289,977 75 were issued December 11, 1883, to W. A. Chase, which construction I do not wish to be understood as claiming.

Having thus described my invention, what I claim is—

1. In an ice-tank for refrigerating structures, the combination, with a horizontal perforated partition dividing said tank into an upper ice-chamber and a lower pickle-chamber, said pickle-chamber having a lateral outlet in its upper end, of an apron suspended in the pickle-chamber directly from the horizontal partition and extending continuously around said chamber, but not in contact therewith at its bottom or sides, whereby a space 90 is afforded for an ascending stratum of pickle between the outer surface of the apron and the inner surface of the pickle-chamber, substantially as described.

2. The combination, with an ice-tank having a horizontal perforated partition, 8, for supporting the ice, and a pickle-chamber located beneath said partition and provided with upper outlet, 12, and lower outlet, 25, of an apron, 22, suspended in said pickle-chamber, 100 a drip-pan, 5, located beneath the pickle-chamber, and a plug-valve, 13, fitted to the lower outlet of the pickle-chamber and provided with an operating-rod, substantially as described. 105

In testimony whereof I have affixed my signature in presence of two witnesses.

ANDREW J. CHASE.
